BENJAMIN A. SLOCUM, OF BINGHAMTON, NEW YORK, ASSIGNOR TO ANSCO PHOTO-
PRODUCTS, INC., OF BINGHAMTON, NEW YORK.

IDENTIFYING MEANS FOR PHOTOGRAPHIC FILMS.

Application filed January 28, 1927. Serial No. 164,263.

It is desirable in the manufacture of photographic film, particularly motion picture film, that the same be provided at the factory with footage indications, preferably the strips of film being numbered consecutively from zero to any given number, these footage indications usually being positioned on the film between the extreme edge thereof and the perforations.

10 These numbers, of course, must be placed on the film in such a manner as to be readily readable when the film is developed and must also, of course, be of such character that neither the numbers themselves nor the 15 method of putting them on will in any way injure the sensitized film for picture taking.

I have devised a novel form of providing motion picture film with these footage numbers which fulfills all the above requirements, which form the objects of this invention.

20 Other objects and advantages in details of form and arrangement will be apparent as the description proceeds, reference now being had to the figures of the drawing wherein like reference numerals indicate like parts.

In the drawing:—

25 Figure 1 is a detail plan view of a portion of a strip of motion picture film provided with the footage numbers in accordance with my invention.

Figure 2 is a detail cross section, greatly enlarged, and taken on the line 2—2 of Figure 1.

30 Figure 3 is a view similar to Figure 1, illustrating the numbers after the film has been developed.

Figure 4 is a detail enlarged view of one of such numbers on the film.

40 The reference numeral 1 refers to a strip of sensitized motion picture film provided with the usual perforations 2. Between the perforations and one edge of the film, I place the footage indications or numbers 3 by stamping or cutting such numbers into the film to a depth equal to the thickness of the sensitized emulsion 4 carried by the film base 5 on the back of which may be the usual gelatine back coating 6 (see Figure 2).

45 50 These numbers 3 may be cut into the emulsion 4 by means of a steel die or other device of any desired or suitable construction and the cutting operation may be assisted by the application of heat to the die if de-

sired. This numbering device is not shown in the drawings as it forms no part of this application and may be of any practical form. Suffice it to say that such numbering is adapted to cut the numbers through the film emulsion as shown clearly in Figure 2, such numbers changing consecutively with each foot of film so marked.

The numbers 3 thus cut in the emulsion of the film are of course visible to the eye at all times, but in order to render them more discernible and clear, after the film has been developed I prefer to expose that portion of the film bearing the numbers as by means of a light flash which serves to fog the film emulsion around such numbers whereby upon development of the film, the numbers will be located within the dark field caused by such flash, thus causing the numbers to stand out in clear relief against the dark back ground. Figure 3 shows the film 1 as developed with the flashed portion 7 around the numbers 3.

55 The apparatus and method for flashing the film around the numbers with light may be of any desired character and may be readily accomplished by a light and shutter arrangement (not shown) attached for operation to the usual perforator through which the film 1 is run for perforation, or to other desired apparatus used in the processing of the film. The flash, of course, is properly masked in order that the light will not expose the film other than at the numbers 3.

60 65 From the foregoing, it will be clear that I have provided a photographic motion picture film with visible footage numbers which are visible both before and after development of the film and in addition have provided means for rendering the numbers very clear and discernible after development. The dark flashed portions 7 about the numbers serves a useful purpose also in the editing of a film provided therewith, as the dark portions appearing at intervals of one 70 foot along the edge of the film serves as a sort of flag to the editor rendering it possible to locate the footage numbers with speed and dispatch.

75 80 85 90 95 100 105 Of course, many changes may be made in details of arrangement and operation without departing from the spirit and scope of my invention. I do not limit myself there-

fore to the exact form shown other than by the appended claims.

I claim:

1. An article of manufacture comprising a strip of sensitized film provided with footage indications cut into the surface of said film, said film being light fogged around said indications.
2. An article of manufacture comprising a sensitized film provided with footage indications adjacent one edge thereof, said indications being cut into the surface of said film whereby they are visible at all times,

said film being light fogged around said numbers whereby upon development, said indications are provided with a dark background.

3. An article of manufacture comprising a strip of sensitized motion picture film perforated adjacent its edges, footage numbers cut into the surface of said film between said perforations and one edge of the film, said film being light fogged around each number only.

BENJAMIN A. SLOCUM.
